(57)

CLAIM

The ornamental design for an electronic tablet, as shown and described.

DESCRIPTION

FIG. 1 is a front isometric view of an electronic tablet showing our new design;

FIG. 2 is a rear isometric view thereof;

FIG. 3 is a front view thereof;

FIG. 4 is a top view thereof;

FIG. 5 is a bottom view thereof;

FIG. 6 is a left side view thereof;

FIG. 7 is a right side view thereof; and,

FIG. 8 is a rear view thereof.

The broken line showing of various features of the electronic tablet is for environmental purposes only and forms no part of the claimed design.
